UNITED STATES PATENT OFFICE.

JOSEPH GOULBOURN, OF LEICESTER, ENGLAND, ASSIGNOR TO UNITED SHOE MANUFACTURING CORPORATION, OF PATERSON, NEW JERSEY, A CORPORATION OF NEW JERSEY.

MACHINE FOR WORKING UPPERS OVER LASTS.

Application filed February 7, 1923. Serial No. 617,608.

To all whom it may concern:

Be it known that I, JOSEPH GOULBOURN, a subject of the King of England, residing at Leicester, in the county of Leicester, England, have invented certain Improvements in Machines for Working Uppers Over Lasts, of which the following description, in connection with the accompanying drawings, is a specification, like reference characters on the drawings indicating like parts in the several figures.

This invention relates to machines for working or shaping uppers over lasts, and has more particular reference to operating means which is moved inwardly over the shoe against resistance of the shoe materials. An instance of such operating means is found in the wiper and tacker unit or units of a well-known type of pulling-over machine (the general characteristics of which, as far as they concern the features of the present invention, are illustrated in United States Letters Patent No. 1,029,387, granted on June 11, 1912, and No. 1,135,954, granted on April 13, 1915, upon applications of R. F. McFeely) and the invention is herein illustrated in its application to mechanism of that general type, which it is one of the objects of the invention to improve in the different respects hereinafter set forth, although it is to be recognized that in many of its aspects the invention is not limited to an organization of that particular type nor to machines including pulling-over means in their organization.

In the type of machine above mentioned each wiper and tacker unit is moved inwardly, to lay or wipe the margin of the upper over the sole and to position the unit for driving the upper fastening tack or tacks, by mechanism which is yieldable in response to resistance encountered by the unit and is intended to yield after the unit has arrived in proper relation to the shoe for the tacking operation. The provision for such yield enables the unit to accommodate itself to different shapes or sizes of shoes, and in the particular type of machine shown in said patent has for a further object to cause the spring-operated tacking means to be released automatically in response to such yield in the operating

connections. Such an organization, however, imposes limitations upon the tightness 55 with which the upper can be fastened on the last and upon the certainty in respect to the position of the upper fastening tacks. These limitations arise from the fact that unless the wipers are advanced well over 60 the edge of the shoe bottom, or at least are pressed hard against the upper before the latter is released by the pulling-over grippers, the tension of the upper is likely to be relaxed more or less before the upper 65 is fastened, and from the further fact that if the wiper mechanism is constructed or adjusted to apply sufficient pressure to afford an adequate margin of safety in this respect, there is danger that in operating 70 on some shoes the resistance encountered by the wipers will be so great as to cause the operating connections to yield prematurely and thus prevent the tacking means from being moved far enough inwardly over the 75 bottom of the shoe prior to the tack driving operation, so that the tacks will not be driven at such distance from the edge of the shoe bottom as to hold the upper 80 properly.

With the object, among others, of avoiding the above mentioned difficulties, the present invention provides, as one important feature, a novel construction and arrangement of means for controlling a device for 85 operating on a shoe (herein shown as a wiper and tacker unit), the construction shown comprising novel means for moving the unit inwardly over the bottom of the shoe through positively acting connections 90 and for limiting the positive movement of the unit as determined by the particular shoe operated upon. In the construction herein illustrated such control is effected by the provision of a cam member which is set 95 or positioned by connections to a clamp engaging the side of the shoe and which acts automatically at a time thus determined to release an element of the positive means provided for moving the wiper and tacker unit 100 inwardly, thus rendering said element yieldable only after the wiper and tacker unit has been moved substantially into proper position for driving the tacks, to accommodate the operating means to different shapes 105 and sizes of shoes without damage to the

machine or to the shoe and, as applied to the particular type of machine illustrated, to cause the tacks to be driven in response to such yield in the operating connections.

5 Further features of the invention are to be recognized in novel means for moving a wiper positively inward over a shoe to a position determined by the shoe, and in novel means for mounting a wiper to permit it to yield universally in directions transverse to its overwiping plane, and it may be, as herein shown, to prevent it from yielding in said plane.

10 The above and other features of the invention, including certain details of construction and combinations of parts, will now be more particularly described by reference to the accompanying drawings and pointed out in the claims.

15 In the drawings,

20 Fig. 1 is a view substantially in front elevation of one of the side wiper and tacker units of a machine of the general type illustrated in said prior McFeely patents, together with a portion of the upper pulling and shoe clamping means, with controlling mechanism constructed in accordance with the present invention applied thereto;

25 Fig. 2 is a side elevation of a part of the mechanism shown in Fig. 1;

30 Fig. 3 is a view partly in plan and partly in section, on an enlarged scale, showing a portion of the means for imparting inward movement to the side wiper and tacker unit, including a portion of the controlling mechanism of the present invention;

35 Fig. 4 is a plan view, on an enlarged scale, of a portion of the shoe clamping means shown in Fig. 1, and

40 Fig. 5 is a section on the line 5—5 of Fig. 4.

45 It will be understood that in the type of machine illustrated the upper is pulled by opposite side grippers, one of which is shown at 2, as well as by a toe gripper, the shoe being held by a sole rest 4 against the pull applied to the upper. While the upper is held by the grippers side clamps are moved 50 inwardly into supporting and holding engagement with the shoe at its opposite sides, these clamps comprising arms 6, one only of which is shown in the drawings, which carry relatively movable clamp members 8 and 55 10 for engaging the shoe in different locations. The member 8 is mounted on a block 12 swiveled in the end of a clamp support or slide 14 so that the clamp member may adjust itself to the shoe about an axis extending heightwise of the shoe. The slide 14 is movable laterally of the shoe in the arm 6 and is connected by rack and pinion mechanism to another slide which carries the member 10, as described more fully in 60 Patent No. 1,135,954.

65 After the clamps have engaged the opposite sides of the shoe the margin of the upper is wiped inwardly over the sole and is fastened, at least at the sides of the forepart, by driving a plurality of tacks spaced along 70 the margin of the sole. For overwiping and tacking the upper at each side of the forepart a wiper and tacker unit is provided comprising a supporting arm 16 which is swung inwardly toward the shoe and carries 75 one or more wiper plates or wipers 18 for engaging the margin of the upper, a pair of such wiper plates being usually provided at each side of the shoe. After the wipers have been moved inwardly far enough to press 80 and hold the upper on the edge of the sole, the arm 16 engages a latch 20 on the gripper to release the gripper from the upper. The wiper plates 18 are carried by a block 85 22 which also carries the tack holders and which is swiveled on the arm 16 to turn, together with tack drivers 24, about an axis extending lengthwise of the arm, as described in the prior patents. The tack drivers 24, which are equal in number to the number of 90 tacks which are to be driven at the side of the shoe, are operated by a spring-impelled driver bar 26 (Fig. 3). The block 22 has fixed thereon an abutment plate 28, and as the arm 16 continues its inward movement 95 after releasing the gripper from the upper this plate is carried into engagement with a stop or abutment shoulder 30 formed on the swivelled clamp block 12. This serves to limit the inward movement of the arm, and 100 also causes the block 22 with its wiper and tacker mechanism to turn about its axis on the arm 16 into the position determined by the shoulder 30 on the swivelled block 12 for locating the wipers and the tackers in 105 the proper angular relation to the edge of the shoe bottom.

110 The mechanism for imparting inward movements to the arms 16 is in many respects similar to the mechanism shown and described in Patent No. 1,029,387, and comprises (Fig. 3) a slide 32 connected to the arm and operated by another slide 34 to which movement is imparted through a gear segment 36. The slide 34 carries a plunger 115 38 which is mounted in a plunger housing 40 in the slide and is controlled by a spring 42, the latter bearing at its outer end on a member 44 which is threaded in the outer end of the housing. The plunger 38 and the slide 32 are provided with cooperating 120 wedge faces 46, whereby, upon yield of the plunger, the slide 34 is permitted to move relatively to the slide 32 in response to resistance encountered by the latter when the arm 125 16 arrives at its limit of inward movement determined by engagement of the member 28 with the shoulder 30. The slide 34 has a part 48 for controlling the driver bar 23, and in the movement of the slide 34 relative- 130

ly to the slide 32 this part releases the driver bar to cause the driving of the tacks, as more fully explained in Patent No. 1,029,387.

For purposes of this invention the machine is provided with mechanism for preventing the plunger 38 from yielding until the arm 16 has arrived in predetermined relation to the shoe, thus insuring against premature release of the tack driving means. For this purpose there is mounted in the member 44 on the plunger housing a locking slide 50, and the plunger 38 is provided with a pin 52 to bear against this slide and prevent the plunger from yielding. The plunger 38 is thus made to serve as a positive connection for moving the arm inwardly to the point required for locating the tacks in proper relation to the edge of the shoe bottom. In order to permit the slide 34 to move relatively to the slide 32 at the time required for releasing the tack driver bar, the locking slide 50 is provided with an opening 54 to receive the pin 52 upon movement of the slide into position for its opening to register with the pin. Such movement of the slide 50, against the resistance of a spring 56, is effected by the action of a controlling cam slide 58 also mounted in a guideway in the member 44 and provided with a cam face 60 for moving the slide 50 as the latter is carried along the member 58 by the movement of the slide 34.

It will thus be evident that the time when the slide 50 is operated to release the plunger 38 depends upon the position of the cam slide 58, and further to accomplish the objects of this invention the position of this cam slide is determined by the shoe by connections between the slide and the shoe engaging clamp member 8. For this purpose the slide 58 is connected by a link 62 to an arm 64 which is pivoted at 66 on a bracket on the frame of the machine, and the arm is connected by a link 68 to the outer end of the slide 14 which carries the clamp member 8, each of the links 62 and 68 being adjustable in length. When the clamp member 8 is carried into engagement with the shoe the cam slide 58 is thus moved preliminarily along its guideway in the member 44 to a position determined by the position of the clamp member, the position of the latter, of course, depending upon the size or shape of the shoe. The shoe is thus rendered effective to determine the point in the inward movement of the arm 16 when the positively acting plunger 38 is released to render it yielding and to cause the driving of the tacks, such release occurring only after the wiper and tacker mechanism has been forced positively inward over the shoe substantially to its limit of movement and substantially at the time when the member 28 is engaged with the shoulder 30 on the clamp member. It will

be understood that the engagement of the member 28 with the shoulder 30, by preventing further inward movement of the arm 16, insures that the slide 34 will move relatively to the slide 32 to release the tack driver bar.

To assist in guiding and supporting the arm 64 a rod 70 is provided which is fixed by a screw 72 in the frame of the machine and is engaged by a yoke 74 (Fig. 2) fast on the arm 64. Nuts 76 adjustably mounted on the rod 70 limit the inward movement of the arm 64 if the machine is operated in the absence of a shoe.

Further to insure that the margin of the upper will be wiped inwardly and held with adequate pressure, the wiper plates 18 are so mounted as to prevent them from yielding in the plane of their inward over-wiping movement, while permitted to yield transversely of said plane as they are forced over the edge of the shoe bottom. For this purpose each wiper plate is provided with a hemispherical boss 78 which is seated in a corresponding cupped recess in the wiper support on the block 22. This boss and the corresponding recess are so shaped and arranged that the wiper may tip universally in directions transverse to the plane of the shoe bottom but is prevented from yielding lengthwise relatively to the support, such tipping movement of the wiper being yieldingly opposed by a spring 80 which bears against its outer end portion.

In order to vary the distance from the edge of the shoe bottom at which the tacks are driven, the clamp member 8 is made adjustable on the swivelled block 12 by the provision of toothed or serrated faces 82 and 84 on these different parts, the parts being clamped together by a headed stud 86 which passes through a slot 88 in the member 7 and is fixed by a cone-pointed screw 90 engaging the stud 86 in a correspondingly shaped notch 92 formed therein. It will be evident that such an adjustment determines the distance of the stop shoulder 30 from the side of the shoe and at the same time serves correspondingly to vary the position of the cam slide 58 when the parts are in clamping position so as to maintain the same coordinate relation between this cam slide and the shoulder 30.

While the invention is herein illustrated in its application to wiper and tacker mechanism arranged to operate at the side of the shoe, it will be understood that the invention is not limited to means for operating upon the shoe in this particular location.

Having described the invention, what I claim as new and desire to secure by Letters Patent of the United States is:

1. In a machine of the class described, the combination with means for operating on a

- shoe movable inwardly over the bottom of the shoe against resistance of the shoe materials, of mechanism for imparting inward movement to said operating means including 5 a member yieldable in response to resistance to such inward movement, a device for preventing said member from yielding to cause it to act positively to impart inward movement to said operating means, and a cam 10 controlled by the shoe for operating said device to release the member at a point in the inward movement of said operating means determined by the shoe.
2. In a machine of the class described, the 15 combination with means for operating on a shoe movable inwardly over the bottom of the shoe against resistance of the shoe materials, of mechanism for imparting inward movement to said operating means including 20 a member yieldable in response to resistance to such inward movement, a device for preventing said member from yielding, a cam for operating said device to release the member at a predetermined point in the inward 25 movement of the operating means, a clamp for engaging the shoe, and connections between said clamp and cam for setting said cam in accordance with the position of the clamp to determine the time of such release.
3. In a machine of the class described, the 30 combination with means for operating on a shoe movable inwardly over the bottom of the shoe against resistance of the shoe materials, of mechanism for imparting inward movement to said operating means including 35 a member yieldable in response to resistance to such inward movement, a slide carried by said mechanism for locking said member against yielding, a controlling member along 40 which said slide is movable constructed to operate the slide to release said yieldable member at a predetermined point in the inward movement of the operating means, and means arranged to be positioned by the 45 shoe for setting said controlling member to determine the time of such release.
4. In a machine of the class described, the 50 combination with means for operating on a shoe movable inwardly over the bottom of the shoe against resistance of the shoe materials, of mechanism for imparting inward movement to said operating means including 55 a spring plunger yieldable in response to resistance to such inward movement, a member for locking said plunger against yielding to cause said operating means to be moved positively inward over the shoe through said plunger, and means controlled by the shoe for operating said locking member to release the spring plunger at a point in the inward movement of the operating 60 means determined by the shoe.
5. In a machine of the class described, the 65 combination with means for operating on a shoe movable inwardly over the bottom of the shoe against resistance of the shoe materials, of mechanism for imparting inward movement to said operating means including 70 a spring plunger yieldable in response to resistance to such inward movement, a device for locking said spring plunger against yielding to cause inward movement to be imparted positively through said plunger to said operating means, a controlling member along which said locking device is movable 75 constructed to operate said device to release the spring plunger at a predetermined point in the inward movement of the operating means, a clamp for engaging the shoe, and connections between said clamp and controlling member for setting said member as determined by the shoe.
6. In a machine of the class described, the 80 combination with means for operating on a shoe movable inwardly over the bottom of the shoe against resistance of the shoe materials, of mechanism for imparting inward movement to said operating means including 85 a member yieldable in response to resistance to such inward movement, a device for locking said member against yielding to cause it to act positively on said operating means, and a cam arranged to operate said locking device to release the member and permit it to yield at a predetermined point in the inward 90 movement of the operating means.
7. In a machine of the class described, the 95 combination with means for operating on a shoe movable inwardly over the bottom of the shoe against resistance of the shoe materials, of mechanism for imparting inward movement to said operating means including 100 a spring plunger yieldable in response to resistance to such inward movement, a member carried by said mechanism for locking said spring plunger against yielding, and a member relatively to which said mechanism is movable for operating said locking member to release the plunger at a predetermined point in the inward movement of the 105 operating means.
8. In a machine of the class described, the 110 combination with means for operating on a shoe movable inwardly over the bottom of the shoe against resistance of the shoe materials, of mechanism for imparting inward movement to said operating means including 115 a spring plunger yieldable in response to resistance to such inward movement, a locking member arranged to engage said plunger to prevent it from yielding and having an opening to receive the plunger, and a cam arranged to move said locking member into position to align its opening with the plunger at a predetermined point in the inward 120 movement of the operating means.
9. In a machine of the class described, the 125 combination with shoe positioning means, of a wiper and tacker unit movable inwardly over the bottom of the shoe and having tack 130

driving means thereon, mechanism for imparting inward movement to said wiper and tacker unit including parts relatively movable in wedging engagement with each other 5 in response to resistance encountered by said unit to release the tack driving means, a device for preventing relative movement of said parts to cause inward movement to be imparted positively to said unit, and a cam 10 for rendering said device inoperative to prevent such relative movement at a predetermined point in the inward movement of the unit.

10. In a machine of the class described, 15 the combination with shoe positioning means, of a wiper and tacker unit movable inwardly over the bottom of the shoe and having tack driving means thereon, mechanism for imparting inward movement to 20 said wiper and tacker unit including a wedge member yieldable in response to resistance to such inward movement to release the tack driving means, a device for preventing said member from yielding, and a 25 cam positioned by the shoe for operating said device to release the member at a point in the inward movement of the unit determined by the shoe.

11. In a machine of the class described, 30 the combination with shoe positioning means, of a wiper and tacker unit movable inwardly over the bottom of the shoe and having tack driving means thereon, mechanism for imparting inward movement to 35 said wiper and tacker unit including a spring plunger yieldable in response to resistance to such inward movement to cause the release of the tack driving means, a locking device carried by said mechanism for preventing 40 the plunger from yielding, a controlling member constructed to operate said locking device to release the plunger at a predetermined point in the inward movement of the unit, a clamp for engaging the shoe, and 45 connections between said clamp and controlling member for setting said member as determined by the shoe.

12. In a machine of the class described, 50 the combination with shoe positioning means, of a wiper and tacker unit movable inwardly over the bottom of the shoe and having tack driving means thereon, mechanism for imparting inward movement to 55 said wiper and tacker unit including a member yieldable in response to resistance encountered by said unit to cause the release of the tack driving means, a device for locking said member against yielding, a cam for operating said locking device to release the 60 member, shoe clamping mechanism having an abutment shoulder arranged to be engaged by the wiper and tacker unit to limit the inward movement of said unit, and connections between the clamping mechanism and said cam for setting said cam in

accordance with the position of the clamping mechanism to effect the release of said member at a time coinciding substantially with the time of engagement of the unit with said abutment shoulder. 70

13. In a machine of the class described, the combination with shoe positioning means, of a wiper and tacker unit movable inwardly over the bottom of the shoe and having tack driving means thereon, mechanism for imparting inward movement to 75 said wiper and tacker unit including a member yieldable in response to resistance to such inward movement to cause the release of the tack driving means, a device for preventing said member from yielding, a controlling member for operating said device to release the yieldable member at a predetermined point in the inward movement of the unit, shoe clamping mechanism including 80 an abutment shoulder arranged to be engaged by said wiper and tacker unit to limit the inward movement of the unit, said clamping mechanism being adjustable to position said shoulder at different distances 85 from the shoe, and connections between the clamping mechanism and said controlling member controlled by the adjustment of said mechanism to determine the time of action 90 of the member in accordance with the distance of said shoulder from the shoe. 95

14. In a machine of the class described, the combination with shoe positioning means, of a wiper and tacker unit movable inwardly over the bottom of the shoe and having tack driving means thereon, mechanism for imparting inward movement to 100 said wiper and tacker unit including a member yieldable in response to resistance to such inward movement to cause the release 105 of the tack driving means, a device for preventing said member from yielding, a controlling member for operating said device to release the yieldable member at a predetermined point in the inward movement of 110 the unit, adjustable means for variably limiting the inward movement of the unit, and connections controlled by adjustment of 115 said limiting means for varying the position of said controlling member in accordance with such adjustment.

15. In a machine of the class described, the combination with shoe positioning means, of a side wiper and tacker unit movable inwardly over the bottom of the shoe 120 and having tack driving means thereon, mechanism for moving said unit inwardly including parts relatively movable in response to resistance to such inward movement to cause release of the tack driving 125 means, and side clamping mechanism having a shoe clamping member and also an abutment shoulder arranged to be engaged by said wiper and tacker unit to limit the inward movement of said unit, said clamp- 130

ing member being adjustable relatively to said shoulder to position said shoulder at different distances from the shoe.

16. In a machine of the class described, the combination with shoe positioning means, of a side wiper and tacker unit movable inwardly over the bottom of the shoe and having tack driving means thereon, mechanism for imparting inward movement to said wiper and tacker unit comprising parts relatively movable in response to resistance to such inward movement to cause release of the tack driving means, said clamping mechanism comprising a support and a block swivelled thereon to turn about an axis extending heightwise of the shoe, said block having an abutment shoulder arranged to be engaged by the wiper and tacker unit to limit the inward movement of said unit, and a shoe engaging clamp member secured on said block and adjustable relatively to the block in directions laterally of the shoe.

17. In a machine of the class described, the combination with shoe positioning means, of a wiper and tacker support movable toward and from the shoe and having tack driving means and a wiper thereon, mechanism for moving said support toward the shoe including a member yieldable in response to resistance to such movement of the support to cause the release of the tack driving means, a device for preventing said member from yielding to cause the support to be moved positively through said member, means controlled by the shoe for operating said device to release the member at a point in the movement of the support determined by the shoe, and means for controlling said wiper to prevent it from yielding in the plane of its inward movement over the shoe.

18. In a machine of the class described, the combination with shoe positioning means, of a wiper support, a wiper on said support for wiping the upper inwardly over the bottom of the shoe, and means for

controlling said wiper to prevent it from yielding in its overwiping plane while permitting it to yield universally in directions transverse to said plane. 50

19. In a machine of the class described, the combination with shoe positioning means, of a wiper support, a wiper on said support for wiping the upper inwardly over the bottom of the shoe, and a cupped bearing between said wiper and its support permitting the wiper to tip universally in directions transverse to the plane of the shoe bottom. 55

20. In a machine of the class described, the combination with shoe positioning means, of a wiper support, a wiper on said support for wiping the upper inwardly over the bottom of the shoe, said wiper having a projection thereon arranged to engage in a cupped recess in the support to permit the wiper to tip universally in directions transverse to the plane of the shoe bottom while preventing it from yielding in its overwiping plane, and a spring acting on said wiper to control its tipping movement. 60

21. In a machine of the class described, the combination with shoe positioning means, of a wiper for wiping the upper inwardly over the bottom of the shoe, means for imparting inward movement positively to said wiper, and means controlled by the shoe for determining automatically the limit of such positive movement of the wiper. 65

22. In a machine of the class described, the combination with shoe positioning means, of a wiper for wiping the upper inwardly over the bottom of the shoe, operating means for imparting inward movement positively to said wiper including an element arranged to be rendered yieldable, and automatic means controlled by the shoe for rendering said element yieldable at a time in the inward movement of the wiper determined by the shoe. 75

In testimony whereof I have signed my name to this specification.

JOSEPH GOULBOURN.
